(57) **CLAIM**

The ornamental design for water jet, as shown and described.

DESCRIPTION

FIG. 1 is a front top perspective view of a first embodiment water jet in accordance with the present invention;

FIG. 2 is a right top side perspective view thereof;

FIG. 3 is a left top side perspective view thereof;

FIG. 4 is a back top perspective view thereof;

FIG. 5 is a plan view thereof, wherein the five figured ring drawn in phantom in FIGS. 1-4 has been removed to clearly show the claimed design;

FIG. 6 is a side view thereof;

FIG. 7 is a cross-sectional view thereof, taken along the line 7—7 in FIG. 1;

FIG. 8 is a cross-sectional view thereof, taken along the line 8—8 in FIG. 2;

FIG. 9 is a cross-sectional view thereof, taken along the line 9—9 in FIG. 3; and,

FIG. 10 is a cross-sectional view thereof, taken along the line 10—10 in FIG. 4.
